UNITED STATES PATENT OFFICE.

ALBERT HAYES, OF NEW YORK, N. Y., ASSIGNOR TO CARNOT DEVELOPMENT CORPORATION, A CORPORATION OF NEW YORK.

ROTARY PUMP.

1,395,916.

Specification of Letters Patent.

Patented Nov. 1, 1921.

Application filed September 5, 1917, Serial No. 189,723. Renewed April 1, 1921. Serial No. 457,706.

To all whom it may concern:

Be it known that I, ALBERT HAYES, a citizen of the United States, residing at New York, in the county of New York, State of New York, have invented certain new and useful Improvements in Rotary Pumps, of which the following is a description, reference being had to the accompanying drawings, forming a part hereof.

10 My invention relates to rotary pumps of the class which comprises as features of construction a chamber of cylindrical or approximately cylindrical form having an inlet and an outlet and a carrier mounted to 15 rotate in the chamber on an axis eccentric to the axis of the chamber and carrying gates or pistons arranged to slide in slots in the carrier and guided in their movement as the carrier rotates, by fixed cams in 20 the heads of the chamber.

My invention has for its object to provide a pump of the class above described which will be simple and inexpensive to construct, will be highly efficient in operation and will be free from liability to clogging or injury from sand or grit.

With these and other objects hereinafter explained in view, my invention consists in the construction and combination of elements hereinafter described and claimed.

Referring to the drawings:

Figure 1 is a front elevation of a rotary pump embodying my invention showing the operating parts of the pump in central 35 vertical section.

Fig. 2 is a front view of one of the heads and

Fig. 3 is a cross sectional view of the operating parts on a plane midway between 40 the heads.

In the construction shown in the drawings the chamber comprises two heads 1, 1, a body 2 connecting the two heads and a cylinder 3 carried by the heads and extending 45 through the body 2. The heads 1, 1, are disk shaped as shown and are each provided above their centers with an opening 4 for the shaft 5. They are each also provided near their peripheries with an inwardly extending annular shoulder 6 to receive and support the cylinder 3. The portions of the heads outside the shoulders 6 are turned off to form flanges 8 to fit against and be bolted or otherwise secured to the 55 body 2.

Within the lines of the shoulder 6 the heads are recessed preferably to a depth equal to the depth from the face of the shoulder 6 to the surface of the flange 8, to form a chamber or recess to receive the cams 60 by which the sliding movement of the gates or pistons in the carrier is controlled. Instead of forming, as is common in pumps of this class, a cam groove of uniform width throughout to receive the lugs of the gates 65 or pistons and to guide them throughout their movement by contact with them at opposite points, the cams are so formed that during a portion of the travel of a gate or piston it will be in contact with a guiding 70 surface only on the outside of its lug and during another part of its travel it will be in contact with a guiding surface only on the inside of the lug, the inside of the lug in the one instance and the outside of the 75 lug in the other instance traveling at such distance from any guiding or other surface as to leave free space for the passage of sand or other solid material.

Within the cam recess or chamber above 80 the center of the head, and above the opening 4 for the shaft is formed a crescent 10 the upper or outer edge or wall of which is formed as shown at 12 on the arc of a circle concentric with the head this surface 12 extending to points 12¹ and 12² in a plane slightly below the plane of the center of the opening 4.

Also within the cam recess or chamber but below the opening 4 for the shaft is a 90 second crescent 11. The upper or inner edge or wall of this crescent is formed as shown at 13 on an arc of a circle concentric with the center of the head, this surface 13 extending to points 13¹ and 13² in substantially the same plane with the points 12¹ and 12² of the upper crescent 10. The lower or outer edge or wall of the crescent 11 may be formed on any convenient arc but should be separated from the inner wall of the 95 shoulder 7 by a substantial space.

On the shaft 5 within the cylinder 3 is arranged the carrier 18. This carrier consists of a cylinder fast on the shaft and provided with radial slots 17, here shown as 105 six in number, adapted to permit the gates or pistons 14 to slide in them. These gates or pistons each consist of a plate of a width to fit easily between the inner faces of the shoulders 6 of the heads and having near 110

their inner ends lugs 15 extending outward into the cam recesses in the respective heads, these lugs being preferably as shown formed as stub shafts or axles to carry rings or rollers 16 to lessen friction. These gates or pistons are each of such length relative to the carrier that when it is directly above the center of the shaft its outer edge is slightly within the inner surface of the 10 cylinder 3.

The cylinder 3 extends around and is supported by the outer face of the shoulder 6 its ends abutting against the flanges 8. Midway between its ends this cylinder is circumferentially slotted to form an inlet opening or port 19 and an outlet opening or port 20. The inlet opening extends from a point slightly above the horizontal plane of the shaft 5 to a point nearly in line with the 20 vertical plane of the shaft. The outlet opening extends from a point below the horizontal plane of the shaft to a point somewhat beyond the vertical plane of the shaft.

The body 2 is provided exteriorly with 25 suitable supports 24 connecting it with a base 25 and is provided on one side with a socket 21 to receive the inlet or suction pipe leading from the source of supply and is provided on its top with a socket 22 to receive the delivery pipe. In the construction shown the socket for the delivery pipe is of 30 greater diameter than the socket for the suction pipe an arrangement which by reason of the effectiveness of the construction 35 of the pump as shown is found to be desirable. The body 2 is so constructed that its inner surface from the socket for the delivery pipe to the socket for the suction pipe fits closely against the outer surface 40 of the cylinder 3 and, from a point somewhat below the socket for the suction pipe to the lower end of the outlet opening 20 it also fits snugly against the cylinder. From the lower end of the outlet opening 20 to 45 the socket for the delivery pipe the body 2 is curved outward as shown at 23 to form an enlarged passage leading to the delivery pipe.

The shoulder 6 is provided above and in 50 line with shaft 5 with a recess 30 communicating with the cam recess or chamber and with the outlet opening or port 20 permitting free outflow of liquid carrying sand or grit.

55 In operation as a gate or piston passes downward past the place of the points 12¹ and 13¹ of the crescents it will be thrown outward by centrifugal force so that its outer edge will bear snugly against the interior of cylinder 3 and as the gate or piston continues its movement the centrifugal force will be aided by the weight of the 60 gate or piston the roller 16 resting on the surface 13 of the lower crescent. As the 65 gate or piston moves beyond the vertical

plane of the axis of the shaft it will be drawn or guided inward by the surface 13 so that as it reaches the place of the points 13² and 12² it will be in position to rest against surface 12 of the upper crescent, its 70 weight tending to keep it in contact with this surface.

While the invention is herein shown and described as applied to a rotary pump and is particularly adapted to such use, I wish 75 it to be understood that the invention is not limited to use as a pump but may be applied to a motor or engine it being, of course, understood that when so used the operating fluid which may be water, steam or gas, is 80 to be supplied under pressure to the inlet and allowed to flow freely from the outlet.

Having thus described my invention, what I claim is:

1. The combination of a cylinder having 85 inlet and outlet openings, a cylindrical carrier mounted to rotate eccentrically in said cylinder said carrier being slotted radially, sliding gates mounted in the slots of the carrier to make contact with the interior of 90 the cylinder and having laterally extending portions, heads for the cylinder each having a recess formed therein, guides for said laterally extending portions of the gates within the recesses, the guiding surfaces of said 95 guides being spaced apart from the walls of the recess a distance sufficiently greater than the diametrical extent of the laterally extending portions of the gates to permit of free passage of sediment. 100

2. The combination of a cylinder having inlet and outlet openings, a cylindrical carrier mounted to rotate eccentrically in said cylinder said carrier being slotted radially, sliding gates mounted in the slots of the carrier to make contact with the interior of the cylinder and having laterally extending portions, heads for the cylinder each having a recess formed therein, guides for said laterally extending portions of the gates within the recesses, the guiding surfaces of said 105 guides being spaced apart from the walls of the recess a distance sufficiently greater than the diametrical extent of the laterally extending portions of the gates to permit of free passage of sediment and an open passage leading from the recess to the outlet 110 opening.

3. The combination of a cylinder having inlet and outlet openings, a cylindrical carrier mounted to rotate eccentrically in said cylinder said carrier being slotted radially, sliding gates mounted in the slots of the carrier to make contact with the interior of the cylinder and having laterally extending portions, heads for the cylinder each having a recess formed therein to receive the laterally extending portions of the gates, guides for said laterally extending portion 125 of the gates arranged within the recess on 120 130 135 140 145 150 155 160 165 170 175 180

opposite sides of the center of the recess, one of said guides having its guiding surface on its exterior at a distance from the wall of the recess sufficiently greater than 5 the diametrical extent of the laterally extending portions of the gates to permit of free passage of sediment, and the other guide having its guiding surface on its interior.

- 10 4. The combination of a cylinder having inlet and outlet openings, a cylindrical carrier mounted to rotate eccentrically in said cylinder said carrier being slotted radially, sliding gates mounted in the slots of the carrier to make contact with the interior of the cylinder and having laterally extending portions, heads for the cylinder each having a recess formed therein to receive the laterally extending portions of the gates, 15 guides for said laterally extending portions of the gates arranged within the recess on opposite sides of the center of the recess and independent of the walls of the recess with their ends spaced apart sufficiently to 20 permit of the passage of the laterally extending portions of the gates, one of said guides having its guiding surface on its exterior and the other having its guiding surface on its interior.
- 25 5. The combination of a cylinder having inlet and outlet openings, a cylindrical carrier mounted to rotate eccentrically in said cylinder said carrier being slotted radially, sliding gates mounted in the slots of the carrier to make contact with the interior of the cylinder and having laterally extending portions, heads for the cylinder each having a recess formed therein to receive the laterally extending portions of the gates, 30 guides for said laterally extending portions of the gates arranged within the recess on opposite sides of the center of the recess and independent of the walls of the recess with their ends spaced apart sufficiently to 35 permit of the passage of the laterally extending portions of the gates, one of said guides having its guiding surface on its exterior and the other having its guiding surface on its interior.
- 40 6. The combination of a cylinder having inlet and outlet openings, a cylindrical carrier mounted to rotate eccentrically in said cylinder said carrier being slotted radially, 45 guides for said laterally extending portions of the gates arranged within the recess on opposite sides of the center of the recess and independent of the walls of the recess with their ends spaced apart sufficiently to permit of the passage of the laterally extending portions of the gates, one of said guides having its guiding surface on its exterior and the other having its guiding surface on its interior.

interior, the guiding surfaces of the two guides being formed on arcs having a common center. 50

6. The combination of a cylinder having inlet and outlet openings, a cylindrical carrier mounted to rotate eccentrically in said cylinder said carrier being slotted radially, 55 sliding gates mounted in the slots of the carrier to make contact with the interior of the cylinder and having laterally extending portions, heads for the cylinder each having a recess formed therein to receive the laterally extending portions of the gates, crescent shaped guides for said laterally extending portions of said gates arranged within the recess on opposite sides of the center of the recess and independent of the wall of 60 the recess with their ends spaced apart sufficiently to permit of the passage of the laterally extending portions of the gates, one of said guides having its guiding surface on its exterior and the other having its guiding surface on its interior. 65

7. The combination of a cylinder having inlet and outlet openings, a cylindrical carrier mounted to rotate eccentrically in said cylinder said carrier being slotted radially, 75 sliding gates mounted in the slots of the carrier to make contact with the interior of the cylinder and having laterally extending portions, heads for the cylinder each having a recess formed therein to receive the laterally extending portions of the gates, crescent shaped guides for said laterally extending portions of said gates arranged within the recess on opposite sides of the center of the recess and independent of the 80 walls of the recess with their ends spaced apart sufficiently to permit of the passage of the laterally extending portions of the gates, one of said guides having its guiding surface on its exterior and the other having 85 its guiding surface on its interior, the guiding surfaces of the two guides being formed on arcs having a common center. 90

In testimony whereof I affix my signature this 12th day of May, 1917.

ALBERT HAYES.
